UNITED STATES PATENT OFFICE

122,499

DESIGN FOR A COMBINED PHONOGRAPH REMOTE CONTROL AND REPRODUCING DEVICE

Nels A. Miller, Chicago, Ill., assignor to J. P. See-
burg Corporation, Chicago, Ill., a corporation
of Illinois

Application July 24, 1940, Serial No. 93,888

Term of patent 14 years

To all whom it may concern:

Be it known that I, Nels A. Miller, a citizen of the United States, residing at Chicago, in the county of Cook and State of Illinois, have invented a new, original, and ornamental Design for a Combined Phonograph Remote Control and Reproducing Device, of which the following is a specification, reference being had to the accompanying drawing, forming part thereof.

Fig. 1 is a front perspective view of a combined phonograph remote control and reproducing device embodying my new design, and

Fig. 2 is a top plan view thereof.

I claim:

The ornamental design for a combined phonograph remote control and reproducing device, as shown.

NELS A. MILLER.
